RECORD CARD CONTROLLED MACHINE

Michael Maul, Berlin-Johannisthal, Germany

Application October 10, 1930, Serial No. 487,833
In Germany November 27, 1929

9 Claims. (Cl. 209—110)

The present invention relates to perforated record card controlled machines with stop devices adapted to automatically stop the machine after exhaustion of the card supply and more particularly to machines in which the automatic stop after the exhaustion of the card supply takes place after a delaying period sufficient to feed all cards from the feeding track to the card receiving means and to effect accordingly an "automatic track clearing."

While the invention may be applied to any type of record card controlled machinery wherein cards are fed along a feeding track to card receiving means, it is of particular advantage for automatic sorting machines for perforated record cards in which the cards are fed to a plurality of sorting stations in accordance with the perforations provided in the cards.

It is already known to provide in card controlled tabulating and sorting machines automatic stop devices. In tabulating machines the stop device is under card control and keeps the machine in operation as long as there are cards passing past the analyzing means. If the last card has left the analyzing means, the stop device will become operative due to cyclically controlled contacts or other means and the machine will be stopped after the last card has left the analyzing means. Usually, however, the card must travel still a certain distance from its position beyond the analyzing station of the receptacle and in the known machines the operator must again depress the start key and must keep the same depressed until the last card has arrived in the receptacle. Similarly automatically effective stop means as in tabulating machines have been provided in sorting machines. The sorting machines now in use which are equipped with automatic stop means will automatically stop if the last card has passed beneath the analyzing means. At this time, however, still a number of cards are on the feeding track to the sorting stations and therefore after each automatic stop the operator is compelled to depress again the start key and hold the same depressed until all cards have arrived at the proper sorting station or in the sorting boxes. The restarting of the machine required, though automatic stop means are provided, is due to the fact that said stop means permit only to stop the machine at the end of the machine cycle of the last card and that they do not permit to cause a time delay of more than one, preferably a plurality of machine cycles between the passage of the last card past the an-

alyzing means and the automatic stop of the machine.

It will be readily seen that the advantages which the provision of an automatic stop device in card controlled machinery affords are impaired by the necessity to restart the machine after each automatic stop and to hold the machine in operation as long as required by constant manual depression of the start key until all cards have arrived in the card receiving means. Since a considerable number of automatic stops occur with a certain machine during a day, the time and attention required by the operator for restarting the machine will accumulate to quite a considerable amount, setting aside the fact that great confusion is very likely to happen if the operator forgets to restart the machine only once or if he overlooks that a card is still on the feeding track. Accordingly, the known automatic stop devices not only require time and attention of the operator but are also insufficient insofar as there is no insurance that after exhaustion of the card supply all cards on the feeding track will have been fed into their receptacles before the cards are removed therefrom.

It is now the main aim of the present invention to provide a record card controlled machine with a stop device that will insure that after exhaustion of the card supply all cards are fed to their receptacle or sorting stations before the automatic stop takes place thus avoiding the troublesome necessity to restart the machine each time after the automatic stop and permitting the operator to remove the cards from the receptacles immediately after the stop of the machine without requiring him to watch the feeding track as is necessary with the above mentioned known stop devices for record card controlled machines. It is a further very important feature of the invention that the same insures that track clearing after exhaustion of the card supply will be properly effected under any circumstances so that the operator may be absolutely sure that automatic track clearing has taken place if the machine automatically stops.

Now, broadly it is not new to provide in a perforated record card controlled machine automatic track clearing means. It has already been suggested in a prior patent specification to provide in a sorting machine for record cards automatic stop means which become only operative after a plurality of machine cycles after card exhaustion, thus clearing the card feeding track before the automatic stop of the machine takes place. However, said prior device cannot meet

the practical requirements and necessarily could not do so due to disadvantages which are inherent to its principle of operation. If an automatic stop device with automatic track clearing shall be of practical utility, it is absolutely necessary that it insures that in any event automatic track clearing will take place and that all cards will be fed to the receptacles before the automatic stop occurs. An automatic stop device by which automatic track clearing will take place only under certain circumstances or wherein under certain conditions which practically may occur, no automatic track clearing will be effected, is of less value than no automatic stop device at all and is even objectionable for the simple reason that such device may mislead the operator to believe that in any event automatic track clearing will have been effected before the automatic stop while in fact it has not been effected. This may again cause considerable confusion unless the operator watches carefully the feeding track which, however, would require more attention than a stop device without automatic track clearing. The known stop device for sorting machines with automatic track clearing belongs to the above indicated type of undesirable stop devices. If for instance in said known sorting machine the card feeding means are manually rotated as is frequently done for lubricating or controlling the adjustment of the machine while no cards are in the magazine, a member controlling the automatic stop will be moved from its home position and will not be returned to the same by the cards upon the start of the machine. The result is that the automatic track clearing period will not last long enough to feed all cards to their stations and after the automatic stop cards are left on the feeding track which leads to the above mentioned trouble or confusion.

It is therefore the main object of the present invention to provide an automatic stop device for track clearing which will under any circumstances insure that at the end of the card supply the machine will still be kept in operation long enough to feed all cards from the feeding track to their respective stations and thus the invention provides means which are of real practical utility and upon which the operator can rely under all circumstances.

In order to attain this purpose I provide in a perforated record card controlled machine a stop device which includes a controlling member movable into a delaying position and an interrupting position; said controlling member controls the card feeding means in such a manner that the same remain operative if the controlling member is in delaying position, but the operation of the card feeding means will be automatically stopped if said controlling member is in interrupting position; it is essential for the invention that means are provided which constantly tend to urge said controlling member from delaying position towards interrupting position, that, however, the controlling member is held against the influence of said urging means in delaying position under the control of track analyzer means if cards are passing on said track analyzer; however, if the card run on said track analyzer has ceased the controlling member may follow the influence of said urging means and will be moved to interrupting position; it is, however, another essential feature of the invention that during said movement the controlling member is subjected to the action

of delaying means which delay its movement for a period corresponding at least to the feeding movement of a card from said track analyzer means to the card receiving means.

It is already known to provide delaying devices of various type wherein a controlling member is constantly urged from a delaying position to an interrupting position, the movement of said delaying member being delayed by suitable delaying means if the member moves from delaying to interrupting position. According to the invention, however, the controlling member controls the card feeding track and is held under the control of a track analyzer in its delaying position against the influence of the constantly acting urging means. Through this novel combination the above indicated advantages of the invention are obtained which had not been available heretofore though for many years in record card controlled machines the necessity for reliable and satisfactory delaying devices was quite striking particularly in sorting machines for which the invention is preferably adapted.

The above mentioned urging means include preferably a spring constantly tending to urge the controlling member towards interrupting position if it is held under the control of track analyzer controlled means in delaying position.

The track analyzer means are preferably provided as a track analyzer lever which is resiliently held in the feeding track and is engaged by the cards.

An essential feature of the invention consists therein that the delaying period may be varied, if desired or required. For that purpose the extent of the movement of said controlling member can be varied; preferably, a stop screw for the controlling member is provided for said purpose which may be adjusted from delaying position towards interrupting position whereby the movement of the controlling member towards delaying position can be restricted.

Since various delaying devices of the above indicated type are known per se, it follows that any delaying device of the type referred to may be employed in the combination according to the present invention. The following specification and the annexed drawings refer therefore only to an illustrative, though a preferred embodiment of the invention wherein the stop device is provided in the form of a so called time relay.

In the drawings:

Fig. 1 shows a longitudinal sectional view through a known sorting machine provided with a so called card contact lever.

Fig. 2 shows in a partial sectional view perpendicular to Fig. 1, the card lever and its coordinated contact.

Fig. 3 shows a view of the time relay being in operative connection with the card feeding mechanism of the sorting machine; the protection cover of said relay is partly broken away to clearly illustrate the interior mechanism.

Fig. 4 shows the diagram of the machine.

Fig. 5 shows a section through the controlling mechanism for the sorting chutes.

Fig. 6 shows in an enlarged scale a view of the mechanism according to Fig. 5, however in released position.

Fig. 7 is a fraction of a perforated record card.

The sorter shown in the accompanying drawings comprises a card magazine in which a stack of cards 11 (Fig. 1) is inserted. The cards are gripped from the stack one by one by knives 12

of the continuously rotating knife drum 13 and are fed towards the feeding rollers 14. The feeding rollers 14 are spaced from each other about the width of a card and to each sorting box are coordinated two cooperating feed rollers on each of both sides of the machine. Immediately behind the magazine, however, there are no lower feed rollers coordinated to the upper feed rollers 14, but a contact cylinder 15 is provided in place of said rollers. The brush holder 18 for the analyzing brush is fast to an insulating block 17. The brush holder 18 is slideable along a current supply bar 19 and may be adjusted by means of worm 16 to any record column of the cards. The distribution of the cards into the various sorting boxes (being generally designated at 20) depends upon the time relation of the passage of a hole in the selected column between the analyzing brush and the contact roller 15. The well known sorting mechanism comprises a plurality of narrow sorting chutes 21 terminating in superimposed sorting fingers 22. The ends of the fingers 22 are spaced in accordance with the distance of the hole positions of a record column; at their left ends the various sorting chutes 21 are fastened to holders 23 which on their part are fastened to the walls 24 of the sorting boxes. The cards will therefore be fed into different sorting boxes 20 depending upon their insertion between the fingers 22 at the sorting place. The cards coming from the card stack will therefore, after having been advanced by the knife drum 13, be fed towards the left by the feed rollers 14 fastened to the shafts 25 and will be distributed into their receptacles. The upper and lower shafts 25 as well as the knife drum are driven by a common worm 26 (Figs. 2 and 3) which in turn is driven by the motor of the machine.

The sorting operation proper of the cards between the fingers 22 is effected in a known way and therefore said operation shall only be explained briefly in connection with Figs. 1, 5 and 6. From Fig. 5 may be seen that the sorting fingers 22 rest upon an angle plate 28 and due to their resiliency they will follow said plate upon lowering of the same in the slot being provided in the card support plate 29. The angle plate is normally in the position shown in Fig. 5; if, however, a card hole passes the analyzing brush, the magnet 30 will be energized and will attract its armature 31 against the tension of spring 32. The armature 31 forms a stop pawl for the angle plate 28 so that the angle plate is permitted to rock about its pivot 36 in clockwise direction after the armature 31 has been moved to the left, until a side arm of said angle plate encounters the stop pin 33; the sorting fingers 22 will therefore tend to follow the angle plate 28 into the slot of the support plate 29. As may be seen, however, from Fig. 6,—the time of release of the current impulse for the magnet 30 is dependent upon the position of the hole in the record card 11. Depending upon the position of said hole, the record card will have been moved in the moment in which the magnet 30 is energized, more or less far between the ends of fingers 22 and angle plate 28. Therefore, upon energization of magnet 30 only those sorting fingers 22 are permitted to follow the angle plate 28 downwardly under which the card 11 has not yet passed while the remaining sorting fingers are kept back by the card since the latter rests on its sides upon the support plate 29. In this way, all cards having a hole on the same position will be sorted between the same sorting fingers 22 and

therefore they will be fed into the same sorting boxes, i. e. the cards will be properly sorted according to their perforation. At the end of each analyzing cycle the angle plate 28 being pivoted at 36 will be restored by the cam disk 34 fastened upon one of the shafts 25 and thereby all fingers 22 will be raised and restored to be ready for another sorting operation. During said restoring operation the armature 31 will return under the influence of spring 32 to its position for holding the armature plate 28 so that the latter will be held in its raised position until magnet 30 is again energized.

Now reference will be had to the card lever being arranged behind the sorting fingers 22 (Figs. 1 and 2) which lever analyzes the card feeding track. On the rear wall 38 of the sorting machine is a bracket 39 provided in which the analyzer bell crank lever 40 is pivotally mounted. On this bell crank lever is fastened a projection 41 being drawn by the spring 42 against a pin 43 so that the bell crank lever is normally in the position shown in Fig. 2. In this position the upper head piece 44 of a vertical arm of the bell crank lever 40 extends slightly beyond the guide plan of the cards between the feed rollers 14. The left arm of the projection 41 controls the normally open contact 46. To prevent obstruction of the cards on the head piece 44 of the lever 40, the head 44 is slightly rounded on the front and rear end as may be seen from Fig. 1. The vertical arm of bell crank lever 40 is provided with a slot 48 through which passes the lower feed shaft 25 which in this way forms a guide for the bell crank lever 40. If there is no card over the bell crank lever 40 in the feeding track between the upper and lower feed rollers 14, the contact 46 is open. If, however, cards are fed by the feed rollers over the bell crank lever 40 the head piece 44 will be pressed downwardly and the bell crank lever will be rocked in clockwise direction (Fig. 2) thereby closing the contact 46. The length of the head piece 44 in feeding direction is slightly more than the distance between the two consecutive cards so that the bell crank lever 40 keeps the contact 46 always closed as long as immediately succeeding cards pass on said lever.

As will be seen from Fig. 1 the card lever is arranged immediately before the first right hand sorting box; from the following explanation will be seen that when starting the machine the start key must be depressed long enough until the first card has reached said lever, whereupon the operation of the machine is automatically maintained. However, the contact lever could also be provided in the known way behind the card stack which would however only permit to depress the start key a little less long.

Now the delaying mechanism according to the present invention will be described more in detail. In order to permit, if desired, the adaptation of the relay for machines already in use, an embodiment has been preferred, providing the relay as an independent unit which can be fastened on a suitable place of the machine; the relay must be operatively connected with the driving elements of the machine and further it is only necessary to connect the relay with the current circuit of the machine.

In the illustrated example, the relay being provided with a casing is fastened on the rear wall 38 (Fig. 3) of the sorting machine along which extends the drive worm 26 for the feed

rollers 14; Fig. 3 shows a view of the rear side of the machine.

The time relay is mounted upon a plate 51 fastened on the wall 38 and is covered with a protection cover 52. Upon the plate 51 is a shaft 53 rotatably mounted having on its rear end a gear 54 and on its front end a bevel gear 55. The gear 54 is in mesh with a wheel 56 being fast upon shaft 25 for feed rollers 14, said wheel 56 extending into said casing through a slot in the same. The bevel gear 55 is therefore continuously rotating if the machine is in operation. Since in the machine illustrated, it is assumed that the cards run from the left to the right, the parts will rotate as indicated by the arrows. Upon the plate 51 are bearings 57 fast, carrying a rotatable worm 58 having on its upper end a bevel gear 59; the bevel gear 59 is in mesh with the bevel gear 55. The worm 58 at its upper end has one thread removed. The relay magnet 60 controls a lever 62 pivoted at 61 and carrying a controlling member 63. The spring 64 tends to draw the lever 62 normally to the left against the stop 65 and the springs 66 tend to draw the slide 63 downwardly in contact with the upper end of the adjusting screw 67. However, if the machine is in rest position the controlling member 63 is in its upper interruption position in which a finger 78 rests upon the uppermost thread of the worm, thereby preventing the springs 66 to draw the slide downwardly. The adjusting screw 67 extends downwardly through a slot of the casing 52 and may be adjusted by means of button 68 into different positions, thereby limiting accordingly the downward movement of the member 63. The member 63 carries an insulating pin 69 controlling a contact 70. In the rest position of the machine the relay is in the position shown in Fig. 3 in which the controlling member 63 being in interrupting position keeps the contact 70 open by means of pin 69. If, however, the machine is started the relay magnet 60 will be energized and, as will still be explained, the magnet will remain energized during the operation of the machine. If the magnet 60 is energized it will draw its lever 62 about the pivot 61 to the right so that the member 63—which until this moment has been kept by the projection 78 in the upper dead thread of the spindle—is disengaged from the threads of the spindle and is drawn downwardly under the influence of springs 66 to delaying position. In the same moment the contact 70 controlling the motor circuit, will close; since the magnet 60 remains energized, also the controlling member 63 will remain in its lower delaying position since the projection 78 is disengaged from the threads of worm 58 and consequently contact 70 will remain closed. If, however, due to the exhaustion of the card supply the card lever which analyzes the feeding track interrupts its coordinated contact, also relay magnet 60 will be deenergized. Since already during the passage of the cards on the track analyzer, the member 63 is constantly subjected to the influence of spring 66 which constantly tends together with worm 58 to urge the controlling member 63 from delaying to interrupting position, upon deenergization of magnet 60 said controlling member will be subjected to the action of said urging means which will move the controlling member to interrupting position.

If magnet 60 is deenergized, the spring 64 will draw the lever 62 to the left so that the projection 78 encounters the worm 58 which is contin-

uously rotating if the machine is in operation. Since the motor circuit is controlled by the contact 70 which is still closed, the machine will not yet be stopped. Upon rotation of worm 58 the projection 78 will catch into a groove of the worm 58 and the member 63 will then be moved upwardly until it reaches interrupting position in which its projection 78 rests upon the uppermost thread of the worm; then the pin 69 opens also the contact 70 thereby interrupting the motor current circuit and stopping the machine. During the upward movement of member 63, the worm 58 and springs 66 are coacting and form the delaying means for delaying the movement of the controlling member 63 from its lower delaying position to its upper interrupting position. 90

It will be clearly seen that the delaying period between the deenergization of magnet 60 and opening of contact 70 is determined by the number of revolutions of the worm 58 and the extent of travel of the member 63 is determined by the adjusting position of screw 67. In the illustrated example the screw 67 is adjusted to almost maximum delay and this adjustment of the relay would be sufficient to feed the last card 100 from the magazine over the whole length of the sorting machine to the most distant sorting box whereupon the machine would be stopped by interruption of contact 70. If the relay shall be applied to tabulating machines it is only necessary to limit the travel of member 63 by means of adjusting screw 67. A corresponding adjustment is only necessary if in sorting machines the cards shall be sorted only in one or more boxes near the magazine. 105

The arrangement of the time relay in the current circuit will now be briefly described in connection with the diagram shown in Fig. 4. If (provided main switch 71 is closed) contact 72 is closed by its coordinated start key, the relay magnet 60 is immediately energized and contact 70 will be closed in the above described manner, thereby connecting the motor 73 to both sides of the current source and simultaneously initiating the card feed. Simultaneously with the energization of magnet 60 also relay 74 has been energized and if then the card feed has been started the contact 46 is kept closed by card lever 40 due to the successively following cards; if, therefore, the operator releases again the start key 111 a circuit will be established leading from the left side of the current source over stop contact 75, card contact 46, the contact 79 of relay magnet 74 now being closed which magnet establishes its own stick circuit, and relay magnet 60 to the right hand side of the current source. The cards are then advanced one by one in the above described manner and the distribution of the cards into the various sorting boxes is controlled by the sorting magnet 30. The cam contact 77 interrupts the sorting circuit each time if due to the distance between two subsequent cards no card is under the analyzer brush. If the card supply is exhausted, the contact lever 44 will be rocked to its normal position and the contact 46 opens. 121 Thereby also the circuit of relay 74 and relay magnet 60 will be opened and said relays will be deenergized. The member 62 is then drawn to the left by spring 64. At this time, however, the controlling member 63 is in its lowermost position (delaying position) permitted by the adjusting screw and the contact 70 is still closed thereby causing the motor 73 to remain in operation and to feed the cards to their receptacles. However, upon rocking of the member 62 to the left, 126

the finger 78 (see Fig. 3) comes into engagement with the groove of the worm so that the controlling member will be moved upwardly in unison with the rotation of the card feed mechanism 5 and at the end of this upward movement the insulating pin will interrupt the contact 70 thereby also interrupting the circuit of the motor 73 and finally stopping the operation of the machine.

While there have been shown and described 10 and pointed out the fundamental novel features of the invention as applied to a preferred embodiment it will be understood that various omissions and substitutions and changes in the form and details of the device illustrated and in its operation 15 may be made by those skilled in the art without departing from the spirit of the invention.

What I claim is:

1. In an automatic perforated record card controlled machine, a feeding track for the record cards, means for feeding said record cards along said feeding track to card receiving means, card controlled analyzer means on said feeding track, an automatic stop device under the control of 25 said track analyzer means and controlling the operation of said card feeding means, said stop device including a controlling member being under the control of said track analyzer means and movable into a delaying position and an interrupting position, means under the control of said controlling member for automatically maintaining the card feeding means in operation if said controlling member is in delaying position and for automatically interrupting the operation of 30 the card feeding means if said controlling member is in interrupting position, said controlling member being independently of the passage of cards on said track analyzer means always subjected to the influence of means constantly tending to the influence of means constantly tending to urge the controlling member from delaying position to interrupting position, delaying means permitting to delay the movement of said controlling member from delaying position to interrupting position for a period corresponding 40 at least to the feeding movement of a card from said track analyzer means to said card receiving means, track analyzer controlled means for holding said controlling member upon the passage of cards on said track analyzer means constantly 45 in delaying position against the influence of said urging means and for releasing said controlling member upon interruption of the passage of the cards on the track analyzer means to the influence of said urging and delaying means to permit the controlling member upon reaching of its interrupting position after the predetermined delaying period to interrupt the operation of the card feeding means.

2. In an automatic sorting machine for perforated record cards, a feeding track for the record cards, means for feeding said record cards along said feeding track to a plurality of sorting stations, card controlled analyzer means on said feeding track, an automatic stop device under the 60 control of said track analyzer means and controlling the operation of said card feeding means, said stop device including a controlling member being under the control of said track analyzer means and movable into a delaying position and an interrupting position, means under the control of said controlling member for automatically maintaining the card feeding means in operation if said controlling member is in delaying position and for automatically interrupting the 65 operation of the card feeding means if said controlling member is in interrupting position, said controlling member being independently of the passage of cards on said track analyzer means always subjected to the influence of means constantly tending to urge the controlling member from delaying position to interrupting position, delaying means permitting to delay the movement of said controlling member from delaying position to interrupting position for a period corresponding at least to the feeding movement of a card from said track analyzer means to said card receiving means, track analyzer controlled means for holding said controlling member upon the passage of cards on said track analyzer means constantly in delaying position against the influence of said urging means and for releasing said controlling member upon interruption of the passage of the cards on the track analyzer means to the influence of said urging and delaying means to permit the controlling member upon reaching of its interrupting position after the predetermined delaying period to interrupt the operation of the card feeding means.

trolling member is in interrupting position, said controlling member being independently of the passage of cards on said track analyzer means always subjected to the influence of means constantly tending to urge the controlling member from delaying position to interrupting position, delaying means permitting to delay the movement of said controlling member from delaying position to interrupting position for a period corresponding at least to the feeding movement of a card from said track analyzer means to the remotest sorting station, track analyzer controlled means for holding said controlling member upon the passage of cards on said track analyzer means constantly in delaying position against the influence of said urging means and for releasing said controlling member upon interruption of the passage of the cards on the track analyzer means to the influence of said urging and delaying means to permit the controlling member upon reaching of its interrupting position after the predetermined delaying period to interrupt the operation of the card feeding if all cards on the feeding track have arrived at their sorting stations.

3. In an automatic perforated record card controlled machine, a feeding track for the record cards, means for feeding said record cards along said feeding track to card receiving means, card controlled analyzer means on said feeding track, an automatic stop device under the control of said track analyzer means and controlling the operation of said card feeding means, said stop device including a controlling member being under the control of said track analyzer means and movable into a delaying position and an interrupting position, means under the control of said controlling member for automatically maintaining the card feeding means in operation if said controlling member is in delaying position and for automatically interrupting the operation of the card feeding means if said controlling member is in interrupting position, said controlling member being independently of the passage of cards on said track analyzer means always subjected to the influence of means constantly tending to urge the controlling member from delaying position to interrupting position, said urging means including a spring to the action of which the controlling member is constantly subjected, delaying means permitting to delay the movement of said controlling member from delaying position to interrupting position for a period corresponding at least to the feeding movement of a card from said track analyzer means to said card receiving means, track analyzer controlled means for holding said controlling member upon the passage of cards on said track analyzer means constantly in delaying position against the influence of said urging means and for releasing said controlling member upon interruption of the passage of the cards on the track analyzer means to the influence of said urging and delaying means to permit the controlling member upon reaching of its interrupting position after the predetermined delaying period to interrupt the operation of the card feeding means.

4. In an automatic sorting machine for perforated record cards, a feeding track for the record cards, means for feeding said record cards along said feeding track to a plurality of sorting stations, card controlled analyzer means on said feeding track, an automatic stop device under the control of said track analyzer means and controlling the operation of said card feeding means,

said stop device including a controlling member being under the control of said track analyzer means and movable into a delaying position and an interrupting position, means under the control 5 of said controlling member for automatically maintaining the card feeding means in operation if said controlling member is in delaying position and for automatically interrupting the operation of the card feeding means if said controlling 10 member is in interrupting position, said controlling member being independently of the passage of cards on said track analyzer means always subjected to the influence of means constantly tending to urge the controlling member from delaying 15 position to interrupting position, said urging means including a spring to the action of which the controlling member is constantly subjected, delaying means permitting to delay the movement of said controlling member from delaying 20 position to interrupting position for a period corresponding at least to the feeding movement of a card from said track analyzer means to the remotest sorting station, track analyzer controlled means for holding said controlling member upon 25 the passage of cards on said track analyzer means constantly in delaying position against the influence of said urging means and for releasing said controlling member upon interruption of the passage of the cards on the track analyzer means 30 to the influence of said urging and delaying means to permit the controlling member upon reaching its interrupting position after the predetermined delaying period to interrupt the operation of the card feeding means if all cards on the 35 feeding track have arrived at their sorting stations.

5. In an automatic perforated record card controlled machine, a feeding track for the record cards, motor driven means for feeding said record cards along said feeding track to card receiving means, a card controlled analyzer lever on said feeding track, an automatic stop device under the control of said track analyzer lever and controlling the operation of said card feeding 40 means, said stop device including a controlling member being under the control of said track analyzer lever and movable into a delaying position and an interrupting position, a contact in a controlling circuit of the motor for said card feeding 45 means, said contact being under the control of said controlling member and being closed to maintain the card feeding means in operation if said controlling member is in delaying position and being opened to interrupt the operation 50 of the card feeding means if said controlling member is in interrupting position, said controlling member being independently of the passage of cards on said track analyzer lever always subjected to the influence of means constantly 55 tending to urge the controlling member from delaying position to interrupting position, delaying means permitting to delay the movement of said controlling member from delaying position to interrupting position for a period corresponding at least to the feeding movement of a card from said track analyzer lever to said card receiving means, track analyzer lever controlled means for holding said controlling member upon 60 the passage of cards on said track analyzer lever constantly in delaying position against the influence of said urging means to keep said contact in the motor controlling circuit always closed while cards are passing on the track analyzer lever and for releasing said controlling member upon interruption of the passage of cards on said track analyzer lever to the influence of said urging and delaying means to permit the controlling member upon reaching of its interrupting position after the predetermined delaying period to open said contact in the motor controlling circuit thereby interrupting the operation of the card feeding means.

6. In an automatic perforated record card controlled machine, a feeding track for the record cards, motor driven means for feeding said record cards along said feeding track to a plurality of sorting stations, a card controlled analyzer lever on said feeding track, an automatic stop device under the control of said track analyzer lever and controlling the operation of said card feeding means, said stop device including a controlling member being under the control of said track analyzer lever and movable into a delaying position and an interrupting position, a contact in a controlling circuit of the motor for said card feeding means, said contact being under the control of said controlling member and being closed to maintain the card feeding means in operation if said controlling member is in delaying position and being opened to interrupt the operation of the card feeding means if said controlling member is in interrupting position, 145

track analyzer lever to the influence of said urging and delaying means to permit the controlling member upon reaching of its interrupting position after the predetermined delaying period to open said contact in the motor controlling circuit thereby interrupting the operation of the card feeding means.

6. In an automatic perforated record card controlled machine, a feeding track for the record cards, motor driven means for feeding said record cards along said feeding track to card receiving means, a card controlled analyzer lever on said feeding track, an automatic stop device under the control of said track analyzer lever and controlling the operation of said card feeding means, said stop device including a controlling member being under the control of said track analyzer lever and movable into a delaying position and an interrupting position, a contact in a controlling circuit of the motor for said card feeding means, said contact being under the control of said controlling member and being closed to maintain the card feeding means in operation if said controlling member is in delaying position and being opened to interrupt the operation of the card feeding means if said controlling member is in interrupting position, said controlling member being independently of the passage of cards on said track analyzer lever always subjected to the influence of means constantly tending to urge the controlling member from delaying position to interrupting position, said urging means including a spring to the action of which the controlling member is constantly subjected, delaying means permitting to delay the movement of said controlling member from delaying position to interrupting position for a period corresponding at least to the feeding movement of a card from said track analyzer lever to said card receiving means, track analyzer lever controlled means for holding said controlling member upon the passage of cards on said track analyzer lever constantly in delaying position against the influence of said urging means to keep said contact in the motor controlling circuit always closed while cards are passing on the track analyzer lever and for releasing said controlling member upon interruption of the passage of cards on said track analyzer lever to the influence of said urging and delaying means to permit the controlling member upon reaching of its interrupting position after the predetermined delaying period to open said contact in the motor controlling circuit thereby interrupting the operation of the card feeding means.

7. In an automatic sorting machine for perforated record cards, a feeding track for the record cards, motor driven means for feeding said record cards along said feeding track to a plurality of sorting stations, a card controlled analyzer lever on said feeding track, an automatic stop device under the control of said track analyzer lever and controlling the operation of said card feeding means, said stop device including a controlling member being under the control of said track analyzer lever and movable into a delaying position and an interrupting position, a contact in a controlling circuit of the motor for said card feeding means, said contact being under the control of said controlling member and being closed to maintain the card feeding means in operation if said controlling member is in delaying position and being opened to interrupt the operation of the card feeding means if said controlling member is in interrupting position, 145

- 7
said controlling member being independently of the passage of cards on said track analyzer lever always subjected to the influence of means constantly tending to urge the controlling member 5 from delaying position to interrupting position, delaying means permitting to delay the movement of said controlling member from delaying position to interrupting position for a period corresponding at least to the feeding movement of a card from said track analyzer lever to the remotest sorting station, track analyzer lever controlled means for holding said controlling member upon the passage of cards on said track analyzer lever constantly in delaying position 10 against the influence of said urging means to keep said contact in the motor controlling circuit always closed while cards are passing on the track analyzer lever and for releasing said controlling member upon interruption of the passage 15 of cards on said track analyzer lever to the influence of said urging and delaying means to permit the controlling member upon reaching of its interrupting position after the predetermined delaying period to open said contact in the motor controlling circuit thereby interrupting the operation of the card feeding means if all cards on the feeding track have arrived at their sorting stations.
8. In an automatic perforated record card controlled machine, a feeding track for the record cards, means for feeding said record cards along said feeding track to card receiving means, card controlled analyzer means on said feeding track, an automatic stop device under the control of 30 said track analyzer means and controlling the operation of said card feeding means, said stop device including a controlling member being under the control of said track analyzer means and movable into a delaying position and an in- 35

- terrupting position, means under the control of said controlling member for automatically maintaining the card feeding means in operation if said controlling member is in delaying position and for automatically interrupting the operation of the card feeding means if said controlling member is in interrupting position, said controlling member being independently of the passage of cards on said track analyzer means always subjected to the influence of means constantly tending to urge the controlling member from delaying position to interrupting position, delaying means permitting to delay the movement of said controlling member from delaying position to interrupting position for a period corresponding at least to the feeding movement of a card from said track analyzer means to said card receiving means, means for varying the extent of the movement of said controlling member for permitting adjustment of the delaying period, track analyzer controlled means for holding said controlling member upon the passage of cards on said track analyzer means constantly in delaying position against the influence of said urging means and for releasing said controlling member upon interruption of the passage of the cards on the track analyzer means to the influence of said urging and delaying means to permit the controlling member upon reaching of its interrupting position after the predetermined delaying period to interrupt the operation of the card feeding means.
9. A machine as specified in claim 8 wherein said means for varying the extent of the movement of said controlling member include a stop screw adjustable from delaying position of said controlling member towards interrupting position of the same.

MICHAEL MAUL.
